J. C. MULDER

GREASE MEASURING DEVICE

Filed March 6, 1926

UNITED STATES PATENT OFFICE.

JACOB C. MULDER, OF OAKLAND, CALIFORNIA.

GREASE-MEASURING DEVICE.

Application filed March 6, 1926. Serial No. 92,846.

This invention relates to grease measuring devices.

My present invention is particularly useful for measuring the amount of grease which is dispensed in applying it to automobiles.

An object of my invention is the provision of an efficient grease measuring device.

With the foregoing object in view, together with such other objects and advantages as may subsequently appear, this invention resides in the construction and arrangement of parts hereinafter described and claimed, and illustrated in the accompanying drawings, in which:

15 Figure 1 is a sectional view of the device taken on line 1—1 of Figure 3.

Figure 2 is a fragmentary plan view of the device shown in Figure 1, the dial being partly broken away.

20 Figure 3 is a plan view of the device shown in Figure 1, the cover of the device and the superstructure above it being removed to show the interior mechanism, and

25 Figure 4 is a perspective view of a form of the paddle employed in my device.

Referring to the drawings for a more detailed description thereof, the numeral 5 indicates a circular casing comprising a removable cover 6 and a bottom 7 which has an inlet opening 8 and an outlet opening 9, from which respectively extend an inlet pipe 10 and an outlet pipe 12. The inlet pipe 10 is reduced at its free end and threaded at that end so that it may be attached to a tube which leads to a supply tank containing grease under air pressure. A paddle wheel 14 has its axle 15 journaled in the top 6 and the bottom 7 of the casing in a manner permitting the paddle wheel to be rotated. The paddle wheel 14 is concentric with the circular casing and extends from the under surface of the cover 6 down to the bottom 7. Paddles 15, illustrated in Figure 4, are pivotally mounted in the periphery of the wheel and extend to the inner surface of the casing. The paddles 15 are curved and are provided at their inner ends with cylindrical enlargements 17, which fit in recesses in the periphery of the paddle wheel 14. The lower, inner ends of the enlargements 17 are cut away, as indicated by the numeral 19 in Figure 4.

The periphery of the paddle wheel 14 is notched adjacent each paddle so that the pivoted paddles when turned in towards the wheel, as hereinafter described, form a continuation of the arcuate periphery of the

wheel, as shown by a turned in paddle illustrated in Figure 3. These notches are designated by the numeral 14^a.

The paddle wheel 14, being smaller in diameter than the interior of the casing, there is a circular channel 21 between the wheel and the casing. Beyond the outlet opening 9 is disposed a plate 22 pivotally connected to the casing at 23. The plate 22 is adapted to close the passageway 21 if desired, so that all the grease may be forced into the outlet opening 9. If, however, it is desired to allow some of the grease to pass the outlet opening and to be carried around again, thus regulating the amount of grease passing into the outlet opening, the plate 22 may be adjusted to allow part of the grease to be carried around the channel. For this purpose the end of the plate 22 may be drawn back towards the casing by means of a screw 25, which threadedly engages the casing and which is pivotally secured to the plate 22 by means of a universal joint 26.

It will be noted from Figure 3 that as the wheel 14 rotates, the pivoted paddles or blades 15, as they come in contact with the plate 22, are turned in by the plate toward the wheel. The grease of course fills the notches 14^a and in order to allow the curved blades 15 to be turned in, so as to form a continuation of the periphery of the wheel and not be prevented by the grease from assuming such position, the notches 14^a are cut so as to provide spaces 14^b between the turned in paddles and the inner boundaries of the notches.

The paddle wheel 14 and the blades attached thereto are of course rotated by the incoming grease which is under pressure. After the turned in paddles or blades 15 pass the plate 22, the notched portions 19 of the blades come into contact with an arcuate vertical plate 30 which rises from the bottom of the casing, and are turned by such contact back into their normal position in which they extend to the inner periphery of the casing. The cover 6 of the casing, which is substantially air-tight, is removably secured to the main portion of the casing by means of screws 32.

A vertical circular wall 33 extends upwardly from the cover 6 and is provided with an interior circular flange 34, on which rests a dial plate 35.

According to my invention an indicator 36 is provided to indicate the amount of grease dispensed from the device. Means are pro-

vided whereby the turning of the wheel 14 turns the indicator 36, and such means are herein shown as comprising a train of gears adapted to be actuated by the wheel and to 5 turn a sleeve 37 on which the indicator 36 is mounted, the sleeve 37 being revolvable on the upper end of the axle 15. The gear train comprises a gear wheel 38 keyed to the axle 15' of the wheel 14. The wheel 38 10 meshes with a gear 39, fixed to a pin 40, which is journaled in the cover 6 and the dial plate 35. A gear wheel 41 is also mounted on the pin 40 and engages with a gear wheel 42 which is secured to the sleeve 37. A helical 15 spring 43 encircles the sleeve 37 between the gear wheel 42 and the dial plate 35. This spring keeps the gear wheel 42 in position to mesh with the gear wheel 41. When it is desired to reset the indicator 36, the sleeve 20 37 may be pulled upwardly to disengage the wheel 42 from the wheel 41, the spring 43 yielding to the upward pull on the sleeve 37.

It will be understood that the ratios of the various gears of the above mentioned gear 25 train may be changed to cause the indicator 36 to move over any desired number of degrees of the dial for each revolution of the paddle wheel 14. The size of the device may be made to deliver any desired amount of 30 grease for each revolution of the wheel 14.

In operating the measuring device, it is adapted to be attached through the pipe 10 to a container holding grease under pressure, such for example as air pressure. The grease 35 moves through the pipe 10 and into the body of the measuring device through an aperture 8 in the bottom thereof, and continues its motion through the circular channel 21 and turns the paddle wheel 14 which bears against 40 the paddles 15. Grease leaves the body of the device through the outlet opening 9, and passes through the pipe 12, which may be at-

tached to a tube having a nozzle at the end thereof.

In dispensing the grease to a customer, the 45 indicator 36 should preferably be at a pre-determined division mark on the dial 35, this division mark being regarded as zero. When the desired amount of grease is dispensed, the position of the indicator will indicate the 50 amount of grease which has left the measuring device. After the device has been used in dispensing grease for one customer, the indicator 36 should be reset by pulling upwardly 55 on the sleeve 37, so that the gear 42 is disengaged from the gear 41, whereby the indicator may be rotated without turning the paddle wheel 14. It is of course understood 60 that the device is to be calibrated in order that the indicator may accurately indicate the amount of grease dispensed.

While I have described one embodiment of my invention, modifications thereof may be readily devised without departing from the spirit of my invention, and it is to be understood that such modifications come within the scope of the appended claim.

I claim:

A device of the character described comprising a casing having inlet and outlet openings, a rotatable paddle wheel in said casing and paddles pivoted to said wheel and extending from the periphery thereof to said casing and adjustable means in said casing beyond said outlet opening for varying the area of the passage between said casing and said wheel, said adjustable means comprising a plate pivotally mounted in said casing, a screw pivotally connected to said plate, said screw threadedly engaging said casing, and extending exteriorly thereof whereby the position of said plate may be adjusted exteriorly of the casing.

JACOB C. MULDER.
